CLAIM

The ornamental design for a graphics card adapter light-emitting line as shown and described.

DESCRIPTION

FIG. 1 is a perspective view of a graphics card adapter light-emitting line showing our new design;

FIG. 2 is another perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof; and,

FIG. 8 is a bottom view thereof.

The broken lines shown on the drawings depict portions of the graphics card adapter light-emitting line that form no part of the claimed design.

1 Claim, 8 Drawing Sheets
